(57) **CLAIM**

The ornamental design for a massaging shower head, as shown and described.

DESCRIPTION

FIG. 1 is a front, top, right perspective view of a massaging shower head, showing my new design;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is a front, top, right perspective view of the massaging shower head, shown in the first usage environment;

FIG. 10 is a front, top, right perspective view of the massaging shower head, shown in the second usage environment;

FIG. 11 is a front, top, right perspective view of the massaging shower head, shown in the third usage environment;

FIG. 12 is a front, top, right perspective view of the massaging shower head, shown in the fourth usage environment;

FIG. 13 is a partial enlarged view of FIG. 1;

FIG. 14 is a partial enlarged view of FIG. 1;

FIG. 15 is a partial enlarged view of FIG. 2;

FIG. 16 is a partial enlarged view of FIG. 3;

FIG. 17 is a partial enlarged view of FIG. 3; and,

FIG. 18 is a partial enlarged view of FIG. 8.

The dashed broken lines in the figures are for the purposes of illustrating portions of the massaging shower head that form no part of the claimed design.

The dash-dot-dash broken lines are for notating enlarged views and form no part of the claimed design

The dashed broken lines in the FIG. 9, FIG. 10, FIG. 11, FIG. 12 are for the purposes of indicating the usage environment of the massaging shower head and form no part of the claimed design.

1 Claim, 15 Drawing Sheets
